CURTAIN FIXTURE

Alvin F. Nye, Rochester, N. Y., assignor, by mesne assignments, of one-half to Harry B. Lawson, East Rochester, N. Y.

Application January 12, 1932. Serial No. 586,182

8 Claims. (Cl. 156—26)

My present invention relates to curtains, shades and the like applicable to windows and similar openings to regulate the entrance of light and which usually comprise a spring or other roll at the top from which the body of the curtain is drawn down into operative position and upon which it is rewound, and the invention has for its general object to provide a simple and inexpensive curtain of this character but one of such a substantial character with regard to its 5 mountings or fittings that it may be made in relatively large sizes and, though heavy, operated freely and noiselessly and with a minimum amount of friction. The improvements are directed in part toward the provision of a novel 10 anti-friction bearing and toward arrangements whereby it may act effectively as a dark curtain.

To these and other ends, the invention resides in certain improvements and combinations of 15 parts, all as will be hereinafter more fully described, the novel features being pointed out in the claims at the end of the specification.

In the drawings:

Fig. 1 is a fragmentary front elevation of a 20 window casing or similar support provided with a curtain fitting constructed in accordance with and illustrating one embodiment of my invention;

Fig. 2 is a fragmentary enlargement of a portion of Fig. 1;

Fig. 3 is an enlarged fragment of the curtain 30 edge showing one of the ball bearing sockets;

Fig. 4 is a vertical section on the line 4—4 of Fig. 2 showing the curtain drawn down to an operative position;

Fig. 5 is a similar view, partly in elevation, as 35 to the roll casing, showing the curtain wound upon its roll;

Fig. 6 is a further enlarged horizontal section taken substantially on the line 6—6 of Fig. 2, and

Fig. 7 is a further enlarged fragment of one 40 of the ball bearings shown in Fig. 4, but taken in vertical section through the socket in the curtain by which it is carried.

Similar reference numerals throughout the several views indicate the same parts.

Although I have illustrated my invention as applied to a darkening curtain that is opaque and of solid expanse such as would be used, for instance, in excluding light from a photographic 50 dark room, it will be recognized upon further explanation of the structure that it can be utilized in the fitting, for instance, of window mesh screens.

Referring more particularly to the drawings, 1 55 indicates a window frame or similar support.

Spanning the top thereof and supported by suitable brackets 2 at the ends, in which it telescopically fits, is a substantially semi-cylindrical breast or casing 3. The brackets 2 are secured to the casing, as by screws 4. A winding roll 5, which is hollow or tubular, has a central shaft 6 mounted in suitable bearings in the brackets 2 and surrounded by a suitable coiled winding tension spring 7. The ends of this spring are anchored, respectively, to the roll 5 and the shaft 6 in the manner of an ordinary shade roll, so that the spring will tend to wind the roll in one direction and the withdrawal of a curtain 8 wound thereon from the position of Fig. 5 to that of Fig. 4 will tension the spring. I have referred to the element 6 as a shaft, but in reality it is a stationary drum or spindle.

Associated with the brackets 2 and secured by screws 9 to the side rails or uprights of the supporting frame 1 are a pair of U-shaped guides 10 in which the edges of the curtain 8 travel in a light-tight manner, in the present specific embodiment of the invention. The screws take through slots 11 in the doubled metal plate that constitutes the guide and in a core piece 12 to render the guides adjustable on the frame with respect to the curtain edges. The opposing elements of each guide are stamped out to jointly constitute a substantially cylindrical or tubular bearing portion 13 in which are accommodated with a rolling fit a plurality of ball bearings 14. These are carried in sockets 15 formed, in the present instance, by grommets secured at intervals in the edges of the curtain 8 that extend into the guide, as aforesaid. It will be seen that when these balls are so in place they provide a true and anti-friction bearing for the curtain in all directions, which also tends to keep the curtain taut as to its transverse expanse.

To avoid the difficulty of attempting to wind the ball bearings 14 upon the roll 5 along with the curtain which, in any event, would tremendously increase the diameter of the roll, I provide means in connection with each guide for feeding the balls to the sockets 15 as the curtain is drawn down off of the roll and discharging them back to the same source when the curtain is raised and rewound.

This means, in the present embodiment, is in the form of a curved tube 16 constituting a magazine in which the balls 14 are stored, as shown in Fig. 5. The lower end or mouth of the magazine opens into the tubular portion 13 of the guide toward which the column of balls are thrust by a compression spring 17 reacting against a cap 18, through which the magazine is filled. In the posi-

110

tion of Fig. 5, the whole set of balls is in the magazine, the curtain is wound fully on the roll and the bottom rail of the curtain, indicated at 19, is at the mouth of the magazine.

5 As the curtain is drawn downwardly and a socket 15 comes into register with the magazine, a ball is thrust into such socket by the spring and passes down with the curtain in the tubular guide as first described, successive sockets being successively loaded in the same manner. Upon the return of the curtain during the winding movement, as each ball reaches the mouth of the magazine, it strikes a deflector 20 which thrusts it therein so that the pocket or socket passes empty 15 into the casing 3 and onto the roll, the balls being again accumulated as in Fig. 5. A small guard or lip 21 at the mouth of the magazine associated with the deflector 20, but spaced therefrom a sufficient distance for the curtain to pass between, 20 prevents the balls from a tendency to follow through because of the pressure of the spring.

I claim as my invention:

1. In a device of the character described, the combination with a lateral guide, of a curtain arranged to run with an edge in the guide, said edge being provided with a plurality of sockets, and balls contained in the sockets to cooperate with the guide.

2. In a device of the character described, the combination with a lateral guide, of a curtain arranged to run with an edge in the guide, said edge being provided with a plurality of sockets, balls contained in the sockets to cooperate with the guide, and means for feeding the balls into the sockets as the curtain is run through the guide.

3. In a device of the character described, the combination with a lateral guide, of a curtain arranged to run with an edge in the guide, said edge being provided with a plurality of sockets, and a magazine containing balls communicating with the guide to deliver the balls to the sockets, successively, as the curtain passes the magazine in one direction and adapted to receive the balls 45 from the sockets as the curtain so passes in the opposite direction.

4. In a device of the character described, the combination with a lateral guide, a flexible curtain arranged to run with an edge in the guide and adapted to be wound upon a roll, said edge

being provided with a plurality of sockets, of a magazine containing a plurality of balls for said guide arranged to deliver the balls successively to the respective sockets as the curtain is drawn from the roll, and means for returning the balls to the magazine as the curtain is run back upon the roll. 80

5. In a device of the character described, the combination with a lateral guide, a flexible curtain arranged to run with an edge in the guide and adapted to be wound upon a roll, said edge being provided with a plurality of sockets, of a magazine containing a plurality of balls for said guide arranged to deliver the balls successively to the respective sockets as the curtain is drawn from the roll, said magazine embodying a tubular roll with spring means for urging the balls therethrough, and means for returning the balls to the magazine as the curtain is run back upon the roll. 90

6. In a device of the character described, the combination with a lateral guide having a tubular portion, of a curtain arranged to run with an edge in the guide, said edge being provided with a plurality of sockets and balls contained in the sockets and running in the tubular portion of the guide. 100

7. In a device of the character described, the combination with a lateral guide having a tubular portion, a flexible curtain arranged to run with an edge in the guide and adapted to be wound upon a roll, said edge being provided with a plurality of sockets traversing the tubular portion, of a magazine containing a plurality of balls for the guide communicating with the guide to deliver the balls successively to the tubular guide and hence to the respective sockets as the curtain is drawn from the roll, and means for returning the balls to the magazine as the curtain is run back upon the roll. 110

8. In a device of the character described, the combination with a lateral guide, a flexible curtain arranged to run with an edge in the guide and adapted to be wound upon a roll, of means associated with the guide independently of the curtain roll but cooperating with the curtain as it passes from the roll to provide it with an anti-friction bearing in the guide. 120
